UNITED STATES PATENT OFFICE.

OTTO E. BRAITMAYER, OF NEW YORK, N. Y., ASSIGNOR TO THE TABULATING MACHINE COMPANY, OF NEW YORK, N. Y., A CORPORATION OF NEW JERSEY.

DUPLICATING MACHINE.

Application filed July 23, 1923. Serial No. 653,063.

The present invention is directed to improvements in card punching apparatus.

In the tabulating machine art it is the common practice to punch cards with perforations which designate various sorts of statistical data. These cards are then utilized in sorting and tabulating machines to obtain various classified records of the data on the cards. In the use of such tabulating systems from time to time it becomes necessary to duplicate comparatively large groups of cards.

Such duplications have heretofore been performed by hand punching operations and accordingly have been time consuming, expensive and difficult. Furthermore, copied cards which depend upon the operator's reading the previously punched card are subject to errors.

In making such duplicated cards it is sometimes desirable to suppress a part of the data derived from the original punched card and, in other cases, it is desirable to rearrange the punched data on the new cards in a different manner and in different fields and columns than that of the original cards.

It is further desirable to provide for automatically effecting punching of certain repetition data on the new cards and for disposing such repetition data in any desired fields or columns thereof.

The present invention is directed to provision of a machine in which groups of punched cards and blank cards may be placed and which, when in operation, automatically feeds the punched and blank cards therethrough, reads the punchings of the punched cards and effects a corresponding punching of the blank cards.

Provision is made for permitting the suppressing of punching of desired data derived from the punched cards and provisions are also made for permitting the transposing of data derived from a given field or column upon the punched cards to other fields or columns upon the to be punched cards.

Provision is also made for automatically punching repetition data in any selected fields on the new cards and for suppressing certain data derived from the original cards and, if desired, impressing other data as selectively determined by a setting of the machine.

Other objects and advantages will be more fully set forth in the accompanying specifica-

tion and claims and shown in the drawings which, by way of illustration, portray a preferred embodiment of the invention.

In the drawings,

Fig. 1 is a side elevation of the machine.

Fig. 2 is a vertical sectional view taken on line 2—2 of Fig. 4.

Fig. 3 is a similar view taken on line 3—3 of Fig. 4.

Fig. 4 is a side view of the machine looking from the right in Fig. 1.

Fig. 5 is a side elevational view of the opposite side of the machine.

Fig. 6 is a detail sectional view taken on line 6—6 of Fig. 4.

Fig. 7 is an enlarged detail view of certain of the parts shown in Fig. 2 in moved position.

Fig. 8 is a detail view of one of the contact devices taken on line 8—8 of Fig. 4.

Fig. 9 is a view of one of the punched cards.

Fig. 10 is an enlarged detail view of certain of the parts shown in Fig. 3 in moved position.

Figs. 11 and 12 are detail views of contact devices taken respectively on lines 11—11 and 12—12 of Fig. 4.

Fig. 13 is a circuit diagram.

Broadly the present invention contemplates, first, supply and discharge receptacles for both punched and unpunched cards. Second, means is provided for feeding the punched and unpunched cards from the supply magazine into the discharge stack. Suitable reading means are provided for sensing the perforations in the already punched cards and these reading devices selectively control the operation of punches which act upon the blank cards.

In addition to the above, means, such as a plug-board, is provided to permit the rearranging of the data derived from the original card on the new card.

Means are also provided for suppressing the making of perforations derived from a part of a card column and, if desired, putting a new designation upon the new card in the same column.

Further means are provided for suppressing the making of all perforations upon the new card derived from a particular field of the original card and, if desired, a means is provided for the making upon the new perforation or group of perforations which repre-

sent a number which is repeated for each new card.

In the drawings, the machine shown comprises the usual frame members which carry

- 5 a main drive shaft 10 driven in any suitable manner as by a motor not shown. The gear train, shown in Fig. 1, is adapted to drive a reciprocating picker crank 11, upper and lower feed rolls 12 and 13, and the stacker rolls 14.
- 10 It will be understood that the feed rolls, picker mechanism and stacker devices are duplicated, one set being provided for the punched or original cards and a second set for the unpunched or blank cards. These
- 15 parts operate concurrently.

In Fig. 3, the original cards are taken from the supply stack 15 by the picker and are delivered to the feed rolls and by other mechanism are delivered to the discharge rolls 13

- 20 which in turn pass the cards to the stacker which delivers them to the discharge stack 16.
- 25 In Fig. 2 there is shown a similar arrangement of parts adapted to deliver the new or unpunched cards from the supply pocket 17 to discharge stack or pocket 18.

Both the original and new cards in their transit from the upper feed rolls 12 to the lower feed rolls 13 are advanced by a step by step motion in order to permit the punching of the new cards while they are at rest. Reading of the perforated cards may be effected while the said cards are in motion and such sensing or reading controls the operation of the punches, which operation takes

- 30 place at a later time in the card cycle.
- 35 Referring to Fig. 3, the shaft 10 carries a cam 19 having a pivoted follower 20 connected to a vertically slidable rack 21 meshing with a pinion 22 fixed to a shaft 22 carrying gears 23 which in turn mesh with vertical racks 24. The stepped arrangement of the cam contour of cam 19 provides for a step by step descent of racks 24 and cam 19 also provides for a quick return of the racks.
- 40 Each rack 24 is suitably guided for vertical movement in the frame of the machine and carries a rearwardly extending portion which supports clip mechanism adapted to receive and grasp the cards.

- 45 The clip mechanism comprises an anvil 25, pivoted upon spring actuated cooperating clip members 26, said members having a locking arm 27 cooperating with a stepped latching dog 28. Fig. 7 shows the clips released from the locking dog and engaging the card C and holding the latter against anvil member 25. Each clip is provided with an extending lip or shoulder adapted to engage under the edge of the card to properly register the same upon the clip carriage. Release of the card and opening of the clips is effected by a cam element 29 which is adapted to engage a pin 30 carried by locking arm 27 when the clip carriage has reached its extreme lowermost position (see Fig. 10). The

clips 26, after release in lowermost position, travel upwardly with the carriage out of the card path, as in Fig. 10, being retained in such position by locking dog 28. Just before reaching the extreme upper position preparatory to receiving a card the clips are released by means of a fixed pin 31 carried by the frame of the machine. This pin strikes the dog and rocks the same to release the clips.

To ensure the upper cards properly engaging the clip mechanism in proper register and to ensure the ejection of the cards into engagement with the lower discharge feed rolls, I provide upper and lower fingers 32, 33 actuated by the linkage 34-35 from cams 36-37 on shaft 38. This shaft is driven by the gear train shown in Fig. 1. The arrangement of the linkage is such that the fingers 32-33 are projected back of the rear edge of the two cards and then lowered to contact with the cards and properly position and deliver the same. Upon the upward movement of the fingers which takes place upon the step by step downward movement of the card carriage, the fingers are withdrawn rearwardly out of the path of the descending cards. Subsequently the fingers are elevated and projected back of the top edges of the next pair of cards.

Perforation reading devices.

Disposed across the section of the machine past which the punched cards travel is a common bar 40 carrying brushes 41 and cooperating through the perforations in the card with contact blocks 42. This brush arrangement is thus commonly used in tabulating machines and requires no detailed description.

The contact blocks are connected through a plugboard 43 (Figs. 4 and 13) to be hereafter described to selector magnets 45. Each selector magnet is adapted to control a particular punch as will now be described.

The punches 46, one of which is provided for each column to be perforated on the new card, are slidably carried by a frame 47 and impelled through the card by means of a common actuating bar 48. This bar is slidably mounted in the frame of the machine and is vibrated back and forth by a cam 49 cooperating with follower 50 attached to said bar. Cam 49 is fast to a shaft 51 which is driven by gearing 52 from shaft 10 (see Fig. 2).

To select the particular punch or punches for operation according to the energization of the selector magnets 45, selector abutment members 53 are provided which normally assume the position shown in Fig. 2. Upon the energization of a particular magnet 45 its armature is attracted and a call wire 55 drawn to the right, swinging pawl 56 anticlockwise and releasing a T-shaped lever 57 so that a spring 58 may rock the latter and project the

selector finger in between the punch and the actuating bar 48. The subsequent displacement (see Fig. 7) of the actuating bar displaces the previously selected punches through the new card. Such displacement is effected while the card is at rest. To restore the punches pivoted fingers 60 are provided which engage shoulders on the punches. These finger devices are actuated by a bail 61 which is directly connected to the actuating bar so as to be moved by the latter (see Fig. 7). For restoring the T-members 57 and elevating the selector fingers 53 and for relatching the pawls 56, I provide a bell crank member 63 pivoted upon shaft 64 and carrying a cross shaft 65 underlying the T-shaped levers 57. The bell crank 63 is vibrated at the proper time in the cycle by means of a pin 66 on disc 67 fixed to cam shaft 61. In this manner the various parts are restored preparatory to the next punching operation. A suitable restoring spring 68 is provided to lower the cross rod 65 after restoring has been completed.

Referring now to the circuit diagram (Fig. 13), it will be noted that two supply mains 70—71 are provided. Bar 40 is connected to the main 70. The various contacts 42 of which only three are shown are connected by suitable wires, such as 72, to plug points 73 on plug-board 43. The selector magnets in turn are wired to various plug points 74 on the plug-board. The return circuit for the selector magnets 45 comprises a wire 75 which leads to cam contact devices 76 and thence through wire 77 to main 71. The purpose of the cam contact devices 76, 76^a is to make the circuit to the selector magnets at such time when cards are under the brushes and to break the circuit at other times, for example, during the interval between cards. These cam contacts are similar to those commonly used in tabulating machines for this purpose.

The purpose of the plug points 73—74 is to permit cross-plugging whereby the data derived from any particular field may be cross-plugged so that perforations may be made either in the same or a different field. In the diagram the cross connection 78 indicates a "direct across" connection. It is obvious that the connections may be "direct across" or transverse or a combination of both.

The cam contacts 76—76^a are mounted on the main drive shaft 10. Upon this shaft is a sleeve 79 which carries a plurality of groups of slotted wheels. One group comprises seven wheels marked 80 and the other group comprises in the present embodiment a single wheel marked 81. Also fast to the sleeve is an indicating wheel or disc 82. This disc is notched upon its periphery to receive a dog 83 fast to a member 84 slidably mounted upon shaft 85. A clutch shifter fork 86 is fast to member 84 and coacts with a pin clutch

87 splined to shaft 10. A suitable pinch lever 88 is carried by the shifter fork element and arranged to engage any one of the three notches 89, 90 and 91 formed in a suitably fixed plate 92. With the parts in the position shown in Fig. 4 the pin clutch is disengaged and the locking dog 83 is engaged in the notch in the periphery of wheel 82 thus holding wheel 82, sleeve 79 and slotted wheels 80 and 81 fixed against rotation. By releasing the pinch lever 88 and shifting the parts to the notch marked 90 the pin clutch 87 is still disengaged from disc 82 but the dog 83 is disengaged from wheel 82. With this position of the parts index wheel 82 may be turned by hand to any desired position thus permitting the insertion of what will be termed clothes pin clips 93 in the slots in the wheel 80 or 81. These so-called clothes pin members act as camming elements to open or close contacts 85 cooperating with each wheel 80 or 81. The contacts 94 are those which are closed by the slugs 93 on the 80 group of notched wheels, whereas the single pair of contacts 95 are adapted to be opened by the slug 93 on the wheel 81. The position of the notches is such that the contacts 94 or 95 will be opened or closed respectively at the times when perforations in the original or punched card are passing under the sensing brushes. For effecting such contact control during the normal running of the machine the pinch lever 88 is shifted to the 91 notch thereby engaging the pin clutch 87 with the disc 82. With the parts thus engaged the wheels 80 and 81 rotate in unison with the shaft 10.

The uses to which the contacts 90, 94 are put may be best understood by referring to the circuit diagram (Fig. 13). It will be noted that contacts 94, of which only one pair is herein shown, are disposed in a circuit 96 extending from main 70 to a group of plug points 97 on the plugboard 43. These plug-board sockets are adapted to be selectively connected to certain of the sockets 74 which are in turn connected to the selector magnets 45. By properly arranging the clothes pin slugs 93 the contacts 94 will energize the selector magnets 45 at the time when they are closed by the slugs 93. In this way predetermined repetition data may be punched on the new cards. This data will be determined by the set-up of the inserted slugs 93. It will be understood of course that plug points 97 can be plugged to any desired plug points 74 thereby permitting the repetition data to be put at any point upon the new card.

Referring now to the tabulator card in Fig. 9, at the extreme right there is shown, an index point column marked 100 in which particular identifying designations are disposed. In some cases it may be desirable where a certain index point is punched out in the original card to suppress the making of a like punching upon the duplicate card. In other cases,

it is desirable that the punching from the original card should not only be suppressed on the duplicate card but a different punching should be made on the duplicate card depending upon the set-up of the machine. Contacts 95 are utilized for controlling this column of the machine. It will be understood, however, that additional columns could be so controlled, in which case additional wheels 81 5 would be provided. Contacts 95 are normally closed contacts which are arranged to be opened by the slugs 93. These contacts are disposed in the circuit 101 leading from the extreme right hand block 42 and extending 10 to plug point position 73*. It will be noted that irrespective of the closure of circuit 101 by its brush, if contacts are opened at the time the card circuit is made, the circuit 101 will be entirely inactive and the selector magnet 45 15 will not be operated. This provides for the suppressing of the perforating on the new card irrespective of a perforation in the original card. One or more slugs 93 will be inserted depending upon how many perforations it is desired to suppress. In case it is not only desired to suppress a perforation derived 20 from the original card but to make a new perforation in accordance with the set-up of the machine one of the slugs 93 on wheel 80 together with its controlled contacts 94 is utilized. A slug 93 is inserted into one of the slots in one of the wheels 80 and the corresponding circuit 96 which extends to one of the plug points 97 is plugged up to a supplementary plug socket 102 in the circuit 101* leading to the selector magnet 45. With this setting of the parts the selector magnet 45 will not receive a current impulse at the time a perforation in column 100 comes under the brush 25 but it will receive a current impulse at the time the particular contacts 94 close.

The foregoing construction provides means for suppressing data derived from a perforation in the original card and for punching substituted data upon the new card.

While the present invention is particularly directed to making duplicate cards of a run of initial unpunched cards in certain aspects the invention is not limited to such applications. The devices employed for certain func-

tions also find utility broadly in machines having provision for repeating upon one card data obtained from another card irrespective of whether or not there is a run or succession of either the initially punched cards or unpunched cards. By the term "card duplicating machine" it will be understood that machines are included which do not necessarily repeat and make an exact copy of the data from the initially punched card. Furthermore, this term is not to be construed as a limited one directed to a machine which handles runs of cards whether punched or unpunched.

What I claim is—

1. In a card duplicating machine, in combination with means for automatically and successively feeding punched and unpunched cards into and through the machine, means for reading desired fields of punched data upon the punched cards, means controlled by the reading means for punching said data or selected portions thereof upon any desired fields of the initially unpunched cards, and supplemental means independent of said punchings in the initially punched cards and including selective set up devices adjustable by the operator for effecting the punching of repetition data upon desired fields of the initially unpunched cards.

2. In a card punching machine, in combination, card handling means, punching elements for perforating a succession of cards as they automatically and successively pass through the machine, control means for effecting normal and possibly variable punching of said cards by said elements, means for automatically suppressing the normal and possibly variable punching operation which would occur, under control of said control means, in a certain card column or columns, and a second control means adapted to automatically effect action of said element to punch predetermined perforations in said card column or columns, said latter perforations being automatically repeated under control of said second control means on a series of said cards.

In testimony whereof I hereto affix my signature.

OTTO E. BRAITMAYER.
